[57] **CLAIM**

The ornamental design for a computer keyboard casing, substantially as shown and described.

DESCRIPTION

FIG. 1 is a front perspective view of a computer keyboard casing showing my design;

FIG. 2 is a side elevational view thereof, the opposing side being a mirror image;

FIG. 3 is a bottom plan view thereof;

FIG. 4 is a front elevational view thereof;

FIG. 5 is a rear elevational view thereof;

FIG. 6 is a top plan view of a second embodiment of my new design;

FIG. 7 is a rear elevational view thereof;

FIG. 8 is a side elevational view thereof, the opposite side being a mirror image;

The main keyboard, the keys on the first embodiment and the keyboard panel outline on the second are shown in broken lines for illustrative purposes.

FIG. 1

FIG. 2

FIG. 3

FIG. 4

FIG. 6

FIG. 7

FIG. 5

FIG. 8
